DESIGN FOR A BABY'S FORMULA MIXER
AND CONTAINERRobert A. Warren and Dorothy L. Warren,
Lakewood, Ohio

Application December 4, 1945, Serial No. 124,312

Term of patent 3½ years

(CI. D44—21)

To all whom it may concern:

Be it known that we, Robert A. Warren and Dorothy L. Warren, citizens of the United States, residing at Lakewood, in the county of Cuyahoga and State of Ohio, have jointly invented a new, original, and ornamental Design for a Baby's Formula Mixer and Container, of which the following is a specification, reference being had to the accompanying drawing, forming part thereof.

Fig. 1 is a front elevational view of a food mixer showing our new design, a portion of the screw cap being broken away;

Fig. 2 is a side elevational view; and

Fig. 3 is a side perspective view; and

Fig. 4 is a top plan view.

We claim:

The ornamental design for a baby's formula mixer and container, as shown.

ROBERT A. WARREN.
